US00D649721S

(12) **United States Design Patent**
de Socio

(10) **Patent No.:** US D649,721 S
(45) **Date of Patent:** ** Nov. 29, 2011

(54) **DOG COLLAR**

(75) Inventor: **Bridget de Socio**, New York, NY (US)
(73) Assignee: **Socio X Inc.**, New York, NY (US)
(**) Term: **14 Years**
(21) Appl. No.: **29/370,292**
(22) Filed: **Jun. 25, 2010**
(51) LOC (9) Cl. 30-04
(52) U.S. Cl. D30/152
(58) Field of Classification Search ..... D30/151-155, D30/144, 199, 160; 119/792-798, 850, 855-859, 119/863-865, 654, 905, 907, 815, 712, 802, 119/784, 769, 760, 776, 862; 242/381.1-381.2, 242/385.4, 378.3, 376.1, 385.1, 916, 601, 242/570, 405, 404, 371, 223, 170, 388.1, 242/405.2, 377, 381.3, 381.6, 405.3, 388.6, 242/384.7, 382, 396.1, 404.1, 380; 362/108; 33/767, 769, 414; D12/400; D3/229, 230, D3/207, 208, 215; 40/1.5, 455, 640, 303; 206/63.3, 459.5, 702, 408; D6/515; D8/358, D8/360, 347, 360.1, 359, 356, DIG. 1; D24/145; D10/57, 104, 72; D20/28; 224/666, 678; 16/445; 283/74, 70; D11/232, 200, 216, D11/1, 2, 86, 87, 201, 206-210, 212-215, D11/218; 24/163 K, 122.3, 323, 702, 600.4-600.7, 24/163 R, 169-171, 173, 177-179, 191, 194, 24/195, 197, 200, 303, 616, 635, 313, 615, 24/3, 6, 3 K, 599.2, 96, 221, 237, 311, 312, 24/314, 321, 338, 339, 309; 428/3, 4; 54/76; 63/29.1, 3; 191/12.2 R, 12.4; D13/154, D13/153, 137.4, 155; D19/69, 67; 379/438; 446/26; 473/576; D22/140; 174/135; 439/504, 439/13, 501; D34/33; 188/83, 82.1, 65.1; 254/134.3 FT; D29/124; D2/627, 624, 633, D2/625; 132/145, 146, 148; 2/314; 59/79.1

(57) **CLAIM**

The ornamental design for a dog collar, as shown and described.

DESCRIPTION

FIG. 1 is a top view of a dog collar according to the present invention;

FIG. 2 is a bottom view thereof;

FIG. 3 is a right side view thereof;

FIG. 4 is a left side view thereof;

FIG. 5 is a front view thereof; and,

FIG. 6 is a rear view thereof.

The broken lines shown in the figures are for illustrative purposes only and form no part of the claimed design.
